US00D898188S

(12) **United States Design Patent** (10) Patent No.: **US D898,188 S**
(45) Date of Patent: **** Oct. 6, 2020**

(54) **SURGICAL MASK**(71) Applicant: **REVOLUTIONARY MEDICAL DEVICES, INC.**, Tucson, AZ (US)(72) Inventors: **Michael J. Pedro**, Windham, NH (US);
Ryan G. Redford, Tucson, AZ (US);
David M. Kane, Tucson, AZ (US)(73) Assignee: **Revolutionary Medical Devices, Inc.**, Tucson, AZ (US)(***) Term: **15 Years**(21) Appl. No.: **29/626,489**(22) Filed: **Nov. 17, 2017**(51) LOC (12) Cl. **29-02**

(52) U.S. Cl.

(57) **CLAIM**

The ornamental design for a surgical mask, as shown and described.

DESCRIPTION

FIG. 1 is top perspective view of a surgical mask in accordance with our invention;

FIG. 2 is a side perspective view thereof;

FIG. 3 is a bottom perspective view thereof;

FIG. 4 is a front elevation view thereof;

FIG. 5 is a rear elevation view thereof;

FIG. 6 is left side elevation view thereof;

FIG. 7 is a right side elevation thereof;

FIG. 8 is a top plan view thereof; and,

FIG. 9 is a bottom plan view of thereof.

Portions of the article shown in broken lines form no part of the claimed invention.

1 Claim, 7 Drawing Sheets
